(57) **CLAIM**

The ornamental design for a faucet set as shown and described.

DESCRIPTION

FIG. 1 is a front, left and top perspective view of a valve of a faucet set in FIG. 1.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of the faucet of the faucet set in FIG. 9.

FIG. 10 is a rear, right and bottom perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof.

FIG. 16 is a bottom plan view thereof.

FIG. 17 is another front, left and top perspective view of the faucet set in a first usable state; and,

FIG. 18 is another front, left and top perspective view of the faucet set in a second usable state.

The dashed broken lines depict portions of the faucet set that form no part of the claimed design.

1 Claim, 18 Drawing Sheets
